UNITED STATES PATENT OFFICE.

HENRY WILKINSON, OF HARTFORD, CONNECTICUT, ASSIGNOR TO EPHRAIM MAGILL
WILKINSON, OF BRIDGEPORT, CONNECTICUT.

STEAM-BOILER OF THE VERTICAL-WATER-TUBE TYPE.

1,152,135.

Specification of Letters Patent. Patented Aug. 31, 1915.

Application filed December 3, 1914. Serial No. 875,263.

To all whom it may concern:

Be it known that I, HENRY WILKINSON, a citizen of the United States, residing at 141 Whitney street, Hartford, in the county 5 of Hartford and State of Connecticut, have invented certain new and useful Improvements in Steam-Boilers of the Vertical-Water-Tube Type, of which the following is a specification.

10 This invention relates to improvements in steam boilers of the vertical water tube type. Heretofore such boilers have been constructed with an upper and lower drum connected by a series of tubes, set vertically and expanded into the heads of the drums. In order to get sufficient heating surface for practical operation it is necessary to make such tubes of considerable length, which in turn necessitates perforating the top head of the 15 upper drum with a series of handholes in order that the tubes may be set in place. Furthermore, head room equal to the length of the tubes must be available above the boiler in order that new tubes may be installed.

The objects of this invention are to construct a boiler in which those disadvantages will be eliminated and which shall embody certain novel, useful and valuable features 20 hereinafter described.

25 The essential features of this invention consist in placing a center drum between the upper and lower drums, thus cutting the tubes into two separate banks, each bank containing tubes of different diameter.

The detailed construction and advantages of this design are hereinafter described.

In order that my said invention and the manner of carrying same into effect or practice, may be properly understood I have 30 hereunto appended two sheets of explanatory drawings in which—

Figure 1 is an elevation of the boiler proper, showing the novel features of this 35 invention. Fig. 2 is a sectional elevation of the boiler set in brick as it would be in usual practice. Fig. 3 is a section to an enlarged scale showing the center drum with the different size tubes expanded into the heads.

40 Referring to the drawings: The usual upper and lower drums *a* and *b* have tubes *c* and *d* expanded into the heads *e* and *f* as shown. A center drum *g* is interposed, preferably midway, between upper and 45 lower drums *a* and *b* thus cutting the tubes

5 into two separate banks as shown at *c* and *d*. The tubes *c* in the upper bank are of larger diameter than the tubes *d* in the lower bank so that the tubes *d* can pass through the tubes *c* as shown in Fig. 3. The upper 60 drum *a* is made slightly longer than the tubes so that the latter can be entered through the manhole *h* and moved to the proper location and dropped through the head into place. In removing one of the 65 tubes *d* in the lower bank the beading is cut off and the tube pulled or pushed through the center drum and up through one of the tubes in the upper bank into the upper drum and out through manhole *h*. 70 A new tube is replaced by reversing these operations.

The tube holes in the heads of all drums are drilled co-axial so that each tube in the lower bank is directly under a corresponding tube in the upper bank. Entrance is made into each drum through manholes *h*, *i* and *j*. A baffle plate *k*, shown in dotted lines in Fig. 3, constructed in sections may be fitted in the center drum to facilitate 75 circulation of the water. The usual baffles *l* are provided to guide the passage of the gases.

It will be seen from the above description and with reference to the accompanying 80 drawings that the cost of renewing a tube in this type of boiler is considerably less than in the type of boiler at present in use, where the tubes are more than twice the length of the tubes in my invention. Furthermore, 85 the amount of head room or clearance required above the boiler is less than one-half that required with the boilers at present in use. When the boiler is placed in a separate boiler house this means a great saving 90 in cost, time and material as the building would not require to be built so high. If the boiler is placed in a building already erected it means a saving in space which can be utilized for other purposes. The tubes 95 being shorter than those in the boilers at present in use are stiffer and less liable to sag or bag. As there are no handholes in the upper drum there are less joints to keep 100 tight. Should a tube burst there is less liability of serious damage as the tubes being shorter, and therefore, stiffer will not thrash around to such a nextent as those in 105 type of boiler now in use. There is a large body of water contained in the center drum 110

to feed the lower bank of tubes, so that there is less liability of the water evaporating out of the tubes nearest the fire so quickly that the water cannot circulate fast enough to supply these tubes so that they are burned. The tubes in the upper bank being larger than the tubes in the lower bank assists the circulation, as the volume of water ascending, expands as it ascends by reason of the 10 additional heat absorbed on its upward passage. The center drum is very beneficial from an economic standpoint, as evaporation in the front of the lower bank of tubes, nearest the grates, is greatly accelerated by 15 the short travel of the steam globules formed within each individual tube, which will discharge into the center drum, and from there find the passage of least resistance to the upper drum. The tubes are more 20 easily cleaned, being shorter than those at present in use and the operation of the tube

cleaner is greatly facilitated by reason of the center drum.

Having thus described my invention I claim:—

In a vertical water tube boiler the combination of an upper, center and lower drum, a series of tubes connecting the upper drum to the center drum and a second series of tubes connecting the center drum to the lower drum, the second series of tubes being of smaller diameter than the first series and adapted to pass through the first series substantially as and for the purposes herein set forth.

In testimony whereof I affix my signature in the presence of two witnesses.

HENRY WILKINSON.
